UNITED STATES PATENT OFFICE.

FREDERICK L. NITSCH AND AUGUST MEIER, OF SYRACUSE, NEW YORK.

ENTRANCE FOR BEEHIVES.

1,387,734.

Specification of Letters Patent. Patented Aug. 16, 1921.

Application filed August 27, 1919. Serial No. 320,159.

To all whom it may concern:

Be it known that we, FREDERICK L. NITSCH and AUGUST MEIER, citizens of the United States, residing at Syracuse, in the 5 county of Onondaga and State of New York, have invented a certain new and useful Entrance for Beehives, of which the following is a specification.

This invention has for its object an entrance for bee hives and particularly a winter entrance which is particularly simple in construction, economical in manufacture readily applied to the hive and highly efficient and durable in use.

15 In describing this invention, reference is had to the accompanying drawings in which like characters designate corresponding parts in all the views.

Figure 1 is a front elevation of my entrance showing the same applied to a hive which is shown fragmentarily.

Fig. 2 is an enlarged sectional view on line 2—2, Fig. 1.

Fig. 3 is an inverted plan view of this entrance.

Figs. 4 and 5 are enlarged sectional views on lines 4—4, 5—5, Fig. 3.

Fig. 6 is a rear elevation of this entrance.

This invention comprises generally, a 30 housing having inner and outer walls or front and rear walls formed with openings or slots therethrough, the openings of the inner wall being arranged out of alinement with those of the outer wall and also communicating with the entrance slot of the hive.

1 designates the hive which may be of any suitable form, size and construction, it including a box resting upon a suitable 40 base 2 and having an entrance slot 3 at the lower edge of one of its sides.

4 designates the winter entrance which is in the form of a housing or box quadrangular in cross section and having a top 45 wall 5, front and rear walls 6, 7, and end walls 8, the top wall inclining downwardly from the rear wall toward the front wall.

Preferably, the entrance openings of this housing are provided in the front and rear 50 walls 6, 7 and usually the front wall is formed with a central entrance slot 9 and the rear wall with slots toward the ends thereof, these slots 10 being alined with the end portions of the entrance 3 of the hive.

55 Preferably, the housing is formed from a blank of sheet metal and the top consti-

tutes the body of the blank and the front and rear walls 6, 7 and end walls 8 are flaps bent downwardly, at an angle to the body.

The entrance 6 of the front wall is formed 60 by slotting said front wall to form a flap 11 which is bent upwardly to form a cover for the slot 9.

In use, the entrance is mounted on the base 2 between the sides of the base, the end 65 walls 8 being sprung outwardly far enough to engage the sides of the base and frictionally hold the entrance in position.

This entrance is particularly advantageous in that owing to the arrangement 70 of the openings 9, 10 the bees are protected in cold weather from drafts and snow and furthermore this arrangement prevents robbing, or rather makes the defense of the hive by the bees easy against a robber 75 swarm.

Furthermore, the arrangement of the slots 10 at points spaced apart compels the bees to feed from two different points so that they are always progressing into their 80 winter feed and hence the danger of starving is small, it being understood that the habit of the bee is to feed outwardly from the center and that after they have reached the limit in one direction from the center, they 85 are unable in winter to move fast enough to the other side of the hive before they die of starvation. Hence by the arrangement of the slots 10 at two points the bees will always progress in one direction and will not 90 be compelled to retrace their steps as in hives in which the entrance is centrally located.

What we claim is:

1. An entrance for bee hives comprising 95 a housing in the general form of a quadrangle in cross section and being folded from a blank to have top, front, rear and end walls, the top wall forming the body and the front, rear and end walls being 100 flaps bent downwardly at an angle to the body, the front and rear walls being formed with passages therethrough, substantially as and for the purpose set forth.

2. The combination of a bee hive having 105 an elongated entrance slot at the bottom thereof, of an entrance comprising a housing extending along said slot and including a top, front and rear and end walls, the front wall being formed with a central entrance slot and the rear wall being formed 110 near its ends with slots communicating with

the slot of the hive, the slots of the front and rear walls of the entrance being out of alignment, substantially as and for the purpose described.

- 5 3. An entrance for bee hives comprising a housing in the general form of a quadrangle in cross section folded from a blank to have a downwardly inclined top, and front, rear and end walls, the inclined top 15
10 forming a body and the front, rear and end walls being flaps bent downwardly at an angle to the body, the front and rear walls

being formed with openings therethrough, and the portion of the front wall displaced to form the opening therein being bent upwardly to form a canopy or cover for the opening in the front wall, substantially as and for the purpose described.

In testimony whereof, we have hereunto signed our names at Syracuse, in the county 20
of Onondaga, and State of New York, this 15th day of August, 1919.

FREDERICK L. NITSCH.
AUGUST MEIER.
